Letters Patent No. 2202 Dated Oct. 17-1865

Design for an Emblem of the National Union

The schedule referred to in these Letters Patent and making part of the same.

Ob all whom it may concern:

Be it known that of Horace Harris of Newark, in the County of Essex, and State of New Jersey, have invented a new and original National Union Design, to be wrought in metal, or on paper or the like substance, and do hereby declare that the following is a full and exact description of the same, reference being had to the accompanying drawing, and to the letters of reference, marked theron:

My invention consists in grouping together the American Flag A, the Constitution of the United States B, the Declaration of Independence C, the sword D, the Holy Bible E, the Censer F and the fire G, burning therein, in a compact form for the purpose of a National Union Design.

What I claim as my invention and desire to secure by Letters Patent is, The design for a National Emblem as shown and described.
